UNITED STATES PATENT OFFICE.

CHRISTEN CHRISTENSEN, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

DISCONNECTING SWITCH.

Original application filed June 21, 1923, Serial No. 646,750. Divided and this application filed October 17, 1924. Serial No. 744,117.

This application is a division of my prior application on disconnecting switches, Serial No. 646,750, filed June 21, 1923. One of the main objects of the present invention is to provide an improved electric switch which is so constructed that the operating mechanism is capable of imparting a strong initial force to the switch blade in order to cause it to break contact with the switch terminal or terminals as the case may be.

Disconnecting switches of the type which I shall hereinafter describe in connection with the drawings, are commonly used in conjunction with oil switches in high tension work. In this work the practice is to use one of these switches in the conductor leading from the bus bar to the oil switch and one in the conductor leading from the

oil switch to the outside line. This arrangement is necessary in order to permit repairs or necessary adjustments to be made on the oil switch. Hence, it is obvious that the switches used in conjunction with the

oil switch may in many cases not be operated for long periods. The contact between engaging surfaces must be firm in order to eliminate resistance and also to secure a large area of engagement. The

firm engagement required results in large static friction, making it necessary to apply a strong force on the switch blade to break it away from its corresponding contact terminal.

Another object is the provision of a novel, inexpensive and rugged switch operating mechanism to impart a powerful initial force to the blade to break contact and thereafter to cause the switch blade to move with increased velocity to full open position. This additional feature of the invention makes this type of switch especially adaptable for low tension work where oil switches are not used.

More particularly, this application is confined to that species of switches in which the switch blade extends beyond the terminal with which it makes contact and is operated by means connected to its outer or free end. The broad claims are retained in said parent case. When the operating mechanism is connected to the outer end of the switch blade, the initial force re-

quired to break away the blade from its contact terminal is less than would be required if it were connected to any other part of the blade. This is important since the lever arm through which the force applied to the blade could act would be shorter the nearer the operating mechanism was brought to the fulcrum or pivoting point of the blade. Hence, any force applied to the switch blade at its outer end by means of suitable operating mechanism connected thereto will be more effective in breaking away the blade from its contact terminal than if the same force were applied at any other point of the switch blade.

Other features residing in the construction and arrangement of parts will be apparent from the following detailed description. Some of the improvements in the present application may be applied to switches of other types, and I do not, therefore, intend to limit these improvements to the particular form of switch herein shown and described.

I shall now describe several embodiments of the invention in connection with the accompanying drawings which form a part of the present specification.

In the drawings:

Fig. 1 is a side elevational view of one embodiment of the present invention;

Fig. 2 is a reduced more or less diagrammatic front elevation of the same;

Fig. 3 is an enlarged top plan view of the embodiment shown in Figs. 1 and 2;

Fig. 4 is a side elevational view of another embodiment;

Fig. 5 is a front elevational view of the embodiment shown in Fig. 4;

Fig. 6 is a horizontal sectional view through an arrangement of switch cells or compartments showing switches and switch operating means embodying my present invention in connection therewith; and

Fig. 7 is a vertical sectional view on line 7-7 of Fig. 6.

The switch illustrated in Figs. 1, 2 and 3 is used in high tension circuits and is of the three phase gang type of vertical switch, and comprises six switch units, three of said units, for example the upper three units 5-5-5, being adapted for connection to one side and the lower three units 6-6-6

being adapted for connection to the opposite side of their respective oil switches.

Referring to the side elevation of Fig. 1 where an upper and lower unit is shown more in detail, it will be seen that each upper unit comprises a lower hinge terminal 8 and an upper contact terminal 9, adapted to be connected by a blade or movable switch member 10. In the embodiment illustrated, each of the terminals 8 and 9 consists of a pair of tongues or terminal lugs and each blade 10 comprises two sets of parallel blades (Fig. 3) adapted for embracing the tongues or terminal lugs of the upper contact terminals 9 and pivoted on the tongues or terminal lugs of lower hinge terminals 8 by pivot bolts 12, suitable spring washers being preferably provided to resiliently press the blades into contact with the sides of the terminals. It will be understood that this construction is merely exemplary and that the switch blade may be of the trussed or any other suitable or preferred type and other forms and arrangement of terminals may be employed. Each lower switch unit comprises similar upper hinge terminals 8, lower contact terminals 9 and blade or pivoted switch members 10.

The bases of switch terminals 8 and 9 are mounted on insulator clamps or fittings 14 which fittings are in turn mounted on the outer ends of supporting insulators 15. The inner ends of insulators 15 are mounted through suitable fittings 16 upon mounting bases or panels 17 which are in turn suitably mounted upon the face of wall 7. Terminals 8 of each upper switch unit 5 are electrically connected into the circuit or phase in which the unit is arranged by leading current carrying bars, busses or leads 18 shown as of circular cross section through insulating bushings 19 mounted in wall 7 and electrically and mechanically connecting said leads 18 to terminal lugs projecting from the bases of terminals 8 as shown diagrammatically in Fig. 1. Connection between the terminal lugs and leads may be had for example by slotting the lugs and securing the leads in the slotted portions of the lugs. Terminals 9 of each upper unit 5 are connected into the circuit by leading conductors 20 through insulating bushings 19 in the top wall or horizontal partition 21 and similarly connecting them to lugs projecting from the bases of terminal 9. Lower units 6 are similarly connected into the circuits or phases in which they are arranged through conductors or leads 22 and 23 which lead in through vertical wall 7 and bottom wall or floor 24.

The mechanism for operating the switch units comprises a horizontal shaft 25 rotatably journaled in bearing blocks 26, which blocks 26 are adjustably mounted in supporting channels 27 at the outer ends of sup-

porting arms or brackets 28 mounted at their inner ends upon wall 7 and projecting therefrom. Each of the blades or pivoted switch member 10 of upper and lower units 5 and 6 is connected to operating shaft 25 through an insulating operating link 30. These links 30 each comprise a rod or length of suitable insulation secured at one end in a ferrule or cap 31 and at its opposite end in the socket portion of a ferrule or cap 32. Ferrules 31 have projecting lugs bifurcated as shown in Fig. 2 and the outer ends of arms 34 fixed upon shaft 25 for rotation therewith are pivoted in these bifurcated ends upon pins 35 which pins may be held in place by means of suitable cotter pins as shown. Ferrules 32 have projecting lugs bifurcated as shown in Fig. 2 and the outer ends of arms 34 fixed upon shaft 25 for rotation therewith are pivoted in these bifurcated ends upon pins 35 which pins may be held in place by means of suitable cotter pins as shown. Ferrules 32 have projecting arms 32' (Fig. 3) pivotally connected with a pair of relatively short links 38 and a pair of relatively long links 40 by pins or bolts 41 which project loosely through the adjacent ends of the projecting arms 32' of ferrules 32, links 38 and 40 and are secured in place as by means of suitable washers and cotter pins as shown in Fig. 3. The portions of links 38 through which pins 41 loosely extend have bifurcated hub or sleeve portions 42 which engage between the projecting arms of ferrules 32 and between said arms and links 40 and properly space and position links 38 and 40 and the arms of ferrule 32 on pin 41 and prevent binding at that point.

Links 40 are spaced within their lengths by spacing post 43 and at their inner or wall ends said links 40 are pivoted between lugs 45 projecting from base or panel 17 upon pins 46 which pins may be held in place by cotter pins as shown or otherwise as desired. The inner ends of relatively short links 38 are pivotally connected through pins 48 to the free ends of blades or switch members 10 beyond contact terminals 9.

Operating shaft 25 extends through a vertical wall or partition 50 substantially normal to wall 7 and at its outer end said shaft 25 carries an operating arm 51 fixed thereon. Arm 51 has pivotal connection at 52 with an operating rod 53 which rod 53 extends down to a point conveniently accessible from floor 24. At this point operating rod 53 has pivotal connection through a recurved link 54 with an operating lever 55. Link 54 is pivotally connected through a pivot pin 56 with a lug projecting from operating lever 55. Operating lever 55 is pivotally supported on a pin 57 mounted in a forked bracket 58 which bracket is in turn mounted or attached to wall 50 as by means

of a bracket 58'. When operating handle 55 is in the upper position illustrated, pivotal connection 56 is in the vertical plane of pivot 57 or is thrown past said plane where-
 5 by the operating mechanism is locked against accidental opening. In operating lever 55 the same is thrown or swung downward through approximately 180 degrees to the position shown in dotted lines. By this motion pivot 56 is carried into or past the vertical plane of pivot 57 below said pivot so as to again lock the operating mechanism in its lower position and the switch units in their open position as will be hereinafter
 10 apparent.

With the switch units closed as shown, the operation of this embodiment of the invention is as follows:—

Operating handle or lever 55 is thrown
 20 into dotted line position (Fig. 1). Operating rod 53 is thereby drawn downwardly and common operating shaft 25 is revolved in a counterclockwise direction (Fig. 1). Rotation of arms 34 with shaft 25 draws operating links 30 toward their dotted line positions.

The adjustable mounting of bearing blocks 26 already referred to comprises a slidable mounting of said blocks in channel supports
 30 27 at the outer ends of brackets 28 between set screws 60 through which set screws 60 the positions of blocks 26 may be adjusted forwardly or rearwardly in channel supports 27 as desired. This adjustment permits ad-
 35 justment of the operating shaft 25 toward or from wall 7 and thereby the operating mechanism without adjusting the separate connections with the switch blades. The point of rotation of shaft 25 at which the switch
 40 units are opened and closed may be adjusted by adjusting the position of shaft 25 in this manner and play between shaft 25 and blades 10 may be eliminated or adjusted as desired without adjusting the various operating
 45 links themselves or the pivotal connections therebetween.

While the illustration and description of Figs. 1, 2 and 3 relate to three phase systems, the invention is equally as applicable to a single or any other number of phases. In the foregoing embodiment the units 5 and 6 are illustrated and described as opening and closing together. The operating mechanism may be applied to open one set of switch
 50 units and close the other and vice versa. The lower units instead of being inverted may be mounted in upright position as are the upper units or all of the switch units may be mounted in inverted position should
 55 that be desirable.

In the embodiment illustrated in Figs. 4 and 5 independent operating shafts 65 and 66 are provided for each of the horizontal rows of switch units 67 and 68. As in the
 60 embodiment shown in Figs. 1, 2 and 3 the

upper and lower switch units 67 and 68 which are mounted on vertical wall 69 are staggered relative each other, upper units 67 being arranged in horizontal alignment and lower units 68 arranged in horizontal 70 alignment parallel to units 67.

In this case each switch unit comprises a lower hinge terminal 70 and an upper contact terminal 71 adapted to be connected by a blade or movable switch member 72. Each of the terminals 70 and 71 consists of a tongue or terminal lug and each blade comprises a pair of parallel blades for embracing the terminal lugs of the contact terminals and pivoted on the tongues or lugs of hinge terminals 70 by pivot bolts 73, suitable spring washers being provided to resiliently press the blades into contact with the sides of the terminals. As before, supporting insulators 74 are mounted at their inner ends
 80 upon the face of wall 69 and project therefrom. The outer ends of insulations 74 are provided with fittings 75 upon which terminals 70 and 71 are suitably mounted. Terminals 70 and 71 are electrically connected into the circuits or phases in which the respective units are arranged through conductors or leads 76.

The horizontal switch operating shafts 65 and 66 are rotatably journaled in bearing blocks 78 which blocks 78 are as before, adjustably mounted in supporting channels 79 at the outer ends of supporting arms or brackets 80 between set screws 82 through which said blocks are adjusted forwardly or rearwardly through channels 79 as desired. Supporting arms or brackets 80 are suitably mounted at their inner ends upon wall 69 and project therefrom.

Each of the blades or pivoted switch members 72 of upper switch units 67 is connected to operating shaft 65 through operating or connecting links 84 and 85. Links 84 are fixed at one end upon shaft 65 for rotation therewith and at their opposite ends said links 84 have pivotal connection at 86 with links 85. The opposite ends of links 85 are pivotally connected at 87 with the free ends of blades 72 outwardly beyond contact terminals 71. The blades 72 of the lower switch units are similarly connected to shaft 66 through links 88 fixed upon said shaft 66 for rotation therewith and having pivotal connection at 89 with links 90 which links 90 are in turn pivotally connected at 91 with blades 72 outwardly beyond contact terminals 71.

Links 84—85 and 88—90 form straight or substantially 180 degree toggle connections between shafts 65 and 66 and the switch blades 72. These connections impart a strong initial opening force to blades 72 upon initial rotation of shafts 65—66 in a clockwise direction to secure a positive breaking of contact and thereafter an in-
 125
 130

creased velocity to secure quick movement of the blades to full open position. This powerful initial force is the result of the relatively slight movement of blades 72 which accompanies relatively great initial rotation of shafts 65 and 66. As the pivot ends 86—89 of arms 84—88 move toward a vertical plane through the axis of shaft 65—66, the ratio of the amount of movement of blades 72 to the amount of rotation of shafts 66—67 increases. This results in a multiplying action or increased velocity with a resulting quick movement of the blades to full open positions, which of course is highly desirable in low tension work, but is of no great advantage in high tension work where these switches are used in conjunction with oil switches.

Operating shafts 65 and 66 extend through a vertical wall or partition 92 shown in Fig. 5, but omitted in Fig. 4. Said wall or partition 92 is positioned substantially normal to wall or partition 69. At their outer ends shafts 65 and 66 carry operating arms 93 and 94 fixed thereon. Arm 93 has pivotal connection at 95 with the upper end of a relatively long operating rod 96. Arm 94 has pivotal connection at 97 with the upper end of a relatively short operating rod 98. The lower ends of rods 96 and 98 are pivotally connected through a pin 99 with a pair of lugs 100 projecting from an operating lever 101. Operating lever 101 is pivotally supported on a pin 102 mounted in a bracket 103 which bracket 103 is mounted through an extension 104 upon wall 69. As explained in connection with operating handle 55 when operating handle 101 is in the upper position illustrated, pivotal connections 99 are in the vertical plane of pivot 102 or are swung past said plane whereby the operating mechanism is locked against accidental opening. In operating lever 101 the same is thrown or swung downward through approximately 180 degrees to the position shown in dotted lines. By this motion, pivot pin 99 is carried into or past the vertical plane of pivot 102 below said pivot so as to again lock the operating mechanism in its lower position and the switch units in their open position.

The operating of this embodiment of the invention is as follows:—

With the switch units closed and the operating mechanism in the position shown, operating handle lever 101 is thrown into dotted line position. Operating rods 96 and 98 are thereby drawn downwardly and operating shafts 65 and 66 are revolved or rotated in clockwise direction (Fig. 4). Rotation of arms 84 and 88 with shafts 65 and 66 draws or pulls blades 72 toward open position through links 85 and 90, first with an exceptionally strong force to break con-

tact and thereafter at increased velocity to secure quick movement of the blades to full open position.

This embodiment of the invention is equally as applicable to a single or any other number of phases, and as before while the various units are illustrated and described as opening and closing together it is to be understood that the operating mechanism may be applied to open one set of switch units and close another and vice versa.

As before, the adjustable mounting of bearing blocks 78 in supporting journals 79 between set screws 82 permits adjustment of the points in the rotation of shafts 65 and 66 at which the switch units are opened and closed and also permits eliminating entirely or independently adjusting as desired any play between either of shafts 65 or 66 and blades 72 without adjusting the various operating links themselves or the pivotal connections therebetween.

In Figs. 6 and 7, I have shown the embodiment of Figs. 4 and 5 mounted in parallel vertical compartments or switch cells 110. Cells or compartments 110 are defined by vertical partitions 111 and a back wall 112, upon which wall 112 the switch units are mounted in vertical aligned pairs. Each switch unit of which there is an upper unit 113 and a vertically aligned lower unit 114 in each compartment, comprises hinge and contact terminals 115 and 116 adapted to be connected by a blade or movable switch member 117. Each terminal has a tongue or terminal lug and each blade comprises a pair of blade members for embracing the terminal lugs of the contact terminals and pivoted to the tongues or lugs of the hinge terminals by bolts 118, suitable spring washers being provided as before. Terminals 115 and 116 are mounted on fittings 119 on the outer ends of insulators 120. The inner ends of insulators 120 are mounted through suitable bases or fittings upon wall 112. Terminals 115 and 116 are connected into circuit through conductors, busses or leads 121.

Horizontal switch operating shafts 122 and 123 extend through the cells or compartments 110 and the partitions defining same and are rotatably journaled in bearing blocks 124. Bearing blocks 124 are mounted in vertical partitions 111 with their outer surfaces practically flush with the outer edges of said partitions. The blades of the upper switch units are connected to operating shaft 122 through links 125 and 126. Links 126 extend between the free ends of blades 117 which extend outwardly beyond contact terminals 116 and are pivotally connected with the blades at that point. Blades 117 of the lower units are similarly connected to shaft 123 through links 128 and 129.

Operating shafts 122 and 123 project out-

wardly through end wall 130 (Fig. 6) and at their outer ends carry arms 131 and 132 fixed thereon. Arm 131 has pivotal connection at 133 with an operating link or rod 134 which may comprise a length of insulation or be otherwise formed as in other embodiments. The opposite end of link or rod 134 has pivotal connection with arm 132 at 135 and also at 135, arm 132 has pivotal connection with a second rod or link 136. The lower end of link 136 is pivotally connected at 137 with lug 138 of operating lever 139. Lever 139 is pivotally supported on a pin 140 mounted in a bracket 141 which bracket is in turn mounted through a bracket 142 upon the outer surface of end wall 130. Compartments or cells 110 are closed by a cover or door 143.

In operation lever 139 is swung from its full to its dotted line position, drawing or pulling link 136 downwardly with a resulting counterclockwise rotation of shaft 123 and corresponding counterclockwise rotation of shaft 122 through link 134. Rotation of arms 125 and 128 with shafts 122 and 123 draws or pulls blades 117 into open position through links 126 and 129; first, with a strong force to positively break contact and then at increased velocity to secure quick movement to full open position. The provision for securing a strong initial opening force followed by an increased velocity in a cell or compartment of minimum size and in so simple a manner is a highly important aspect of my invention.

I do not intend to be limited to the precise details illustrated and described.

I claim:—

1. In a switch, in combination, an operating shaft, a contact member, a swinging member extending beyond said contact member, and link mechanism connecting said shaft with the extended portion of said swinging member for actuating it into and out of engagement with said contact member.

2. In a switch, a contact member, a swinging member extended beyond said contact member, an operating shaft, link mechanism connecting said shaft with said swinging member, said mechanism comprising a link fixed to said shaft and a link pivotally connected to the extended portion of said swinging member, and a link connected with said link mechanism and having stationary pivotal support.

3. In a switch, a shaft, a fixed member, a moving member extending beyond and co-operating with said fixed member, and means connected to said shaft and to the extended portion of said moving member capable of exerting a maximum initial force in breaking away said moving member from said fixed member.

4. In combination, a pair of contact terminals, switch members co-operable with

said terminals and having free ends extending beyond same, operating means for said switch members, and toggle mechanism connecting said operating means with the extended portions of each of said switch members.

5. In a switch, a rotatable operating shaft, link means thereon, swinging blade members having extended portions at their free ends, and link means pivotally connected to said first link means and to the extended portions of each of said blade members.

6. In a switch, a rotatable operating shaft, link means thereon, swinging blade members having extended portions, link means pivotally connected to said first link means and to the extended portion of each of said blade members, and arms having stationary pivotal support and connected to said connecting link means.

7. In a switch, a contact member, a plurality of swinging members having portions extending beyond said contact members, and link mechanism connected to the extended portions of said swinging members, said link mechanism being designed so that a strong initial force may first be applied to break away said swinging members from said contact members and thereafter an increased velocity to bring said swinging members to full open position.

8. In a switch, a contact member, a swinging member extending beyond and adapted to engage with said contact member, and a swinging arm connected to the extended portion of said swinging member, the effective length of said swinging arm being a minimum and the effective length of said swinging member being a maximum when said swinging member is engaged with said contact member.

9. In a switch, a shaft, a fixed member, a swinging member cooperating with and extending beyond said fixed member, link mechanism connected to said shaft and to the extended portion of said swinging member, and means provided for actuating said shaft.

10. In a switch, a shaft, a fixed member, a swinging member cooperating with and extending beyond said fixed member, link mechanism connected to said shaft and to the extended portion of said swinging member, and means provided for actuating said shaft, said means comprising a link fixed to said shaft and a link mechanism connected to said fixed link for angularly moving said shaft.

11. In a switch, in combination, a bracket, a shaft mounted on said bracket, a fixed member, a swinging member movable into and out of co-operation with said fixed member and having a portion extending beyond said fixed member which co-operates therewith, and link mechanism connected to

- the portion of said moving member extending beyond said fixed member, and also connected to said shaft.
12. In a switch, a shaft, a link fixed to said shaft, a fixed member, a swinging member cooperating with and extending beyond said fixed member, and link mechanism connected with said fixed link and also connected with said swinging member at its extended portion, the effective length of said fixed link increasing and the effective length of said swinging member decreasing as the swinging member is actuated into full open position.
13. In a switch, in combination, an operating shaft, a plurality of contact members, a plurality of swinging members extending beyond said contact members, link mechanism connecting said shaft with the extended portions of said swinging members for simultaneously actuating them into and out of engagement with said contact members.
14. In a switch, in combination, a rotatable operating shaft having a link centrally fixed thereon, link members pivotally connected to the opposite ends of the link mounted on the shaft, swinging blade members having links connected to their free ends, the free ends of said first links being pivotally connected to the free ends of the links on said swinging blade members, and a link connected to the pivotal connection of the free ends of the free members for properly constraining their motion relative each other.
15. In a switch, in combination, a plurality of brackets, a shaft adjustably mounted on said brackets, a plurality of links centrally fixed to said shaft, a plurality of swinging blade members, and a plurality of link mechanisms pivotally connected to the links fixed on said shaft and to the free ends of said swinging blade members so as to actuate same when the shaft is rotated.
16. In a switch, a movable switch member of decreasing effective length, a pivot terminal for said member, a contact terminal for said member, a pivoted arm of increasing effective length for operating said switch member, a link pivotally connected with the switch member, a second link having pivotal connection with said first link and with said pivoted operating arm, and a link having stationary pivotal support and pivotally connected with said first links.
17. In a switch, a contact terminal, a switch member, an operating shaft, link mechanism connecting said shaft with said switch member, said mechanism comprising a link connected with the shaft and a link connected with the switch member and with said first link and a link connected with said link mechanism and having stationary pivotal support.
18. In a switch, a contact terminal, a switch member, an operating shaft, a link pivotally connected with the switch member, a second link pivotally connected with said first link, said second link having connection with said shaft, and a link pivotally connected with said first links at the point of pivotal connection therebetween, said last link having stationary pivotal support.
19. In combination, a pair of contact terminals, a pair of switch members, an operating shaft, means connecting said operating shaft with each of said switch members, and links having stationary pivotal support and pivotal connection with said connecting means.
20. In combination, a support, a plurality of switch members having stationary pivotal mountings thereon, bearing brackets on said support and projecting therefrom, an operating shaft rotatably journaled on said brackets, link mechanism connecting said shaft with said switch members to operate same upon rotation of said shaft, and means for adjusting the operating shaft on said brackets.
21. In a switch, a movable switch member, a rotatable arm for operating said member, connecting means between said arm and the switch member, and means for adjusting the axis of rotation of said arm.
22. In a switch, a support, a bearing block adjustably mounted on said support, and a switch operating shaft rotatably journaled in said bearing block.
23. In a switch, a supporting bracket, said bracket having a supporting channel, a bearing block adjustable between upright legs of said channel, and a switch operating shaft rotatably journaled in said bearing blocks.
24. In a switch, an operating member, a contact member, a movable switch element extending beyond and cooperating with the said contact member, and means connecting the operating member and the extended portion of the movable element for causing a strong initial force to be applied to separate the element from the contact member and for thereafter moving the element away from the contact member with an increasing velocity.
25. In a switch, a contact member, a movable element extending beyond and cooperating with the said contact member, the said element being movable out of engagement with the contact member through a decreasing effective length, and means operable through an increasing effective length connected to the extended portion of the movable element for moving it.

In witness whereof, I hereunto subscribe my name this 6th day of October, 1924.

CHRISTEN CHRISTENSEN.
